UNITED STATES PATENT OFFICE.

WILLIAM C. KEHR, OF LONDON, KENTUCKY.

ICE-CREAM FREEZER.

1,202,070.

Specification of Letters Patent. Patented Oct. 24, 1916.

Application filed April 20, 1915. Serial No. 22,705.

To all whom it may concern:

Be it known that I, WILLIAM C. KEHR, a citizen of the United States, residing at London, in the county of Laurel and State of Kentucky, have invented a new and useful Improvement in Ice-Cream Freezers, of which the following is a specification, reference being had to the accompanying drawing.

10 My improvement relates particularly to means for placing and retaining the freezer can of ice cream freezers in the freezer tub.

The object of the invention is to provide stability for the freezer can and prevent floating when the ice surrounding the can within the tub becomes melted, and particularly when such melting occurs while the can is made lighter by the removal therefrom of a portion of the ice cream. In this 20 connection it is to be observed that there is decided tendency toward such floating, because the liquid between the tub and the can is heavy on account of the presence of salt therein, while the oils and fats in the 25 ice cream make the latter of relatively lower specific gravity. The "floating" of such ice cream cans is objectionable for several reasons, among which may be mentioned the fact that when the can rises in the liquid, 30 a smaller portion of the can is exposed to the cold of the brine and ice, and the fact that the ice cream in the can is then more difficult to remove by means of a spoon or other similar instrument.

35 In my improved apparatus, the lower portion of the can is detachably engaged in such manner as to be held at a fixed height above the bottom of the tub and so as to leave the can free to rotate on an upright 40 axis in the usual manner.

In the accompanying drawings, Figure 1 is a sectional elevation of a mechanism embodying my improvement; Fig. 2 is a section on the line, 3—3, of Fig. 1, looking upward; Fig. 3 is a section on the same line looking downward; Fig. 4 is a section on the line, 4—4, of Fig. 1, looking downward.

45 Referring to said drawings, A, is a portion of the bottom of the tub, and, B, is the bottom of the can.

C, is a base or pedestal resting upon the bottom, A, and suitably secured thereto, as by means of screws, 1, 1. Said base converges from the bottom upward and termi-

nates in a cylindrical neck, 2, and a spherical head, 3.

On the bottom, B, of the can is a cylindrical block or body, D, having its axis coincident with the axis of the can, and said body is secured to the bottom of the can by means of rivets, 4. Said body, D, is recessed to receive the head, 3, and the neck, 2. At one side of the axial line of said body there is a port, 5, extending upward through the lower face of said body and of proper size to permit said body and the can to move downward, said port receiving the spherical head, 5. From said port there is a passage, 6, extending to and around said axial line. From said port to and around said axial line, the bottom of the body, D, is cut away to a width a little more than equaling the thickness of the neck, 2, thus leaving two lips, 7, below the passage, 6, between which the neck, 2, may move horizontally. On said axial line, a recess, 8, is formed to extend upward from the passage, 6, said recess being of proper size to receive the upper portion of the spherical head, 3. Said recess is preferably made to conform to the upper half of the head, 3, so that when said head rests in said socket, a ball-and-socket joint is formed which will permit the rotation of the can on said axial line and will also permit some leaning of the can from the vertical.

The operation is as follows: When the can is to be placed into the tub, it is moved downward with its axial line at one side of the head, 3, and the neck, 2, the port, 5, being placed above said head. Then the can is moved downward until the head is entirely within the port, 5. Then the can is moved to bring its axial line to coincide with the axial line of said head and neck, 95 said head moving through the passage, 6, and said neck moving between the lips, 7, 7. Such movement is arrested when the head, 3, bears against the wall of the passage, 6, toward which the head has been relatively moving. Then the recess or socket, 8, is above the head, and the can may move downward until the upper half of the head rests in said socket. Ice is then packed into the space between the tub and the can in the usual manner. When the can is rotated for freezing, the head, 3, and the socket, 8, form a journal and bearing for the lower end of

- the can. When there is tendency to float, the can can not move upward farther than is permitted by the lips, 7. Said lips bear against the lower portion of the head. At 5 such time lateral movement of the can is prevented by the ice which surrounds the can. That is the case, even when a large portion of the ice has melted. Furthermore, the lips, 7, are concaved around the axial line, such concave portion and the lower portion of the ball making a ball-and-socket joint, so that when the can pulls upward, the lower portion of the head will rest in said concave portion and form an engagement therein which will prevent sidewise movement of the can. Thus there is a ball-and-socket joint when the can is pressed down by excessive weight and also when buoyancy lifts the can.
- 10 20 When it is desired to remove the can from the tub, the can is moved upward or downward and then sidewise as may be necessary to relatively move the head outward from the axial line of the can through the passage, 6, and then downward through the port, 5.
- The base or pedestal, C, may be varied in height to produce the desired space between the bottom of the tub and the bottom of the can. The length of the neck, 2, must be sufficient to allow the head, 3, to enter the socket, 8, and to permit the head to move downward and then laterally outward through the passage, 6. That calls for making said neck longer than the height of the lips, 7, 7.
- 15 30 35 The head, 3, and the body, D, may be said to form a ball-and-socket joint in which the socket is divided into two parts separated from each other, one being the upper part, 8, and the other being the lower part, 9, (the concaved portion of the lips around the axial line), the passage, 6, leading from between said socket portions, 8, and 9, laterally, and opening through one of the faces of said body.
- 40 45 I claim as my invention—
1. In an apparatus of the nature described, the combination with a tub bottom and a can, of members applied to said bottom and said can for forming a journal and bearing and normally permitting free rotation of said can on an upright axis and holding the can against both upward and downward movement, the bearing being laterally open for the free lateral removal of the journal, substantially as described.
  2. In an apparatus of the nature described, the combination with a tub bottom and a can, of members applied to said bottom and said can for forming a ball-and-socket joint normally permitting free rotation of said can on an upright axis and holding the can against both upward and downward movement, the socket being laterally open for the free lateral movement of the ball, substantially as described.
  3. In an apparatus of the nature described, the combination with a tub bottom and a can, of a base or pedestal secured to one of said members and terminating in a neck and a head, and a body secured to the other of said members and having lips at opposite sides of the upright axial line of the can and having a socket for said head above the latter and having a passage extending laterally from said socket above said lips, substantially as described.
  4. In an apparatus of the nature described, the combination with a tub bottom and a can, of a base or pedestal resting upon and secured to said bottom and terminating in a neck and a head, a body on the bottom of the can and having lips at opposite sides of the upright axial line of the can and having a socket for said head above said lips and having a passage extending laterally from between said socket and said lips, substantially as described.
  5. In an apparatus of the nature described, the combination with a tub bottom and a can, of a base or pedestal resting upon and secured to said bottom and terminating in a neck and a head, a body on the bottom of the can and having lips at opposite sides of the upright axial line of the can and having a socket for said head above said lips and having a passage leading horizontally from between said socket and said lips, and connecting with or terminating in a port opening through the bottom of said body, substantially as described.
  6. In an apparatus of the nature described, the combination with a tub bottom and a can, of a base or pedestal resting upon and secured to said bottom and terminating in a neck and a head, a body located on the bottom of the can and having lips at opposite sides of the upright axial line of the can and having a socket for said head above said lips and having a lateral passage leading from between said socket and said lips, said lips being concaved around the upright axis of the can, substantially as described.
  7. In an apparatus of the nature described, the combination with a tub bottom and a can, of a base or pedestal resting upon and secured to said bottom and terminating in a neck and a head, a body located on the bottom of the can and having lips at opposite sides of the upright axial line of the can and having a socket for said head above said lips and having a passage leading horizontally from between said socket and said lips and terminating in a port opening through the bottom of said body, said lips being concaved around the upright axis of the can, substantially as described.
  8. In an apparatus of the nature described, the combination with a tub bottom and a can, of members applied to said bottom and said can, one of said members com-

sing a head or ball and the other having an upper and a lower socket portion separated from each other by a passage extending horizontally and opening through said member, substantially as described.

9. In an apparatus of the nature described, the combination with a tub bottom and a can, of members applied to said bottom and said can, one of said members comprising a head or ball and the other having an upper and a lower socket portion separated from each other by a passage extend-

ing horizontally and opening through the bottom of said member, substantially as described.

In testimony whereof I have signed my name, in presence of two witnesses, this 20th day of February, in the year one thousand nine hundred and fifteen.

WILLIAM C. KEHR.
